UNITED STATES PATENT OFFICE

EDWARD P. COLE, OF CHICAGO, ILLINOIS

INCINERATOR

Application filed January 20, 1930. Serial No. 421,930.

My invention relates to garbage incinerators and like devices having a heating and drying compartment for the garbage above a combustion compartment and in which the dried out garbage may be passed into the combustion compartment and burned.

The principal objects of my invention are to provide an improved incinerator having combustion and drying compartments, the drying compartment being above the combustion compartment; to drain the water from the garbage in the drying compartment and discharge it so that it will not affect the fire in the combustion chamber; to provide the drying compartment with a rotatably removable floor portion co-operable with a scraper to drop the garbage into the combustion chamber; to provide an improved stepped grate construction and auxiliary gas burners in connection therewith for the combustion chamber; and to provide for other novel and desirable results in a device of the class described.

On the drawings: Fig. 1 is a side elevation of an embodiment of my present invention;

Fig. 2 is a top view of the same;

Fig. 3 is a similar view with the top of the incinerator removed;

Fig. 4 is a partial sectional elevation taken on the line 4—4 of Fig. 5;

Fig. 5 is a central sectional side elevation taken along the line 5—5 of Fig. 2;

Fig. 6 is a sectional plan view taken along the line 6—6 of Fig. 5, and

Fig. 7 is a similar view taken along the line 7—7 of Fig. 5.

Referring more particularly to the drawings, I show an incinerator having a double wall casing 1 in which is a combustion chamber or compartment 2 and a drying chamber or compartment 3 thereabove. Separation of the two chambers is effected by a rotatable floor plate 4 and an inclined partition 5, the latter of which is secured in any suitable manner within casing 1 adjacent the top as at 6 and has its lower edge 7 terminating immediately above plate 4. A supporting member 8 is secured within and extends across casing 1 and has a central bearing 9 for a vertical

shaft 10. Casing 1 is provided with a cover 11 having a flue opening 12, a door 13 and a guide bearing 14 also for shaft 10.

Plate 4 is semi-circular and has a peripheral drain groove 15 along its circular edge discharging at the ends thereof adjacent the side walls of the incinerator, this plate 4 also has an upstanding sleeve 16 midway on the straight rear edge 17. The plate has a slight downward slope from radial element 18 to assist in draining. A scraper 19 is suitably secured to shaft 10 so as to rotate with it and has a lower edge 20 which is slightly above inclined partition 5, and a handle 21 is affixed to shaft 10 just above the cover 11.

In the lower compartment and suitably secured therein are a number of gas burners 22 and 23 and over the burners are grates 24 and 25. Grates 24 and 25 have outwardly extending shafts 27 and 28 which are squared at their ends 29 and 30, for the application of rock cranks 31 and 32. Burner 22 and grate 24 are elevated above the level of burner 23 and grate 25 and are substantially under plate 4 in the normal position shown in Fig. 5. Adjacent grates 24 and 25 are guide grate members 33 and 34. The usual ash door 35 and ash pan 36 are also provided. Partition 5 has a by-pass opening 37 in its upper portion and a removable cover 38 is provided for the opening.

The operation of the device is as follows: With plate 4 in the position shown in Fig. 5 cover door 13 is opened and compartment 3 filled with garbage or other refuse which will fall upon plate 4 and partition 5 piling up on the latter as in a hopper. There will ordinarily be a certain amount of free or entrapped water or moisture in the garbage, the free part of which water will drop on plate 4 either directly or from partition 5 and because of the slope of the plate will be carried to peripheral groove 15 and discharge therefrom at the sides of the incinerator. Burners 22 and 23 upon being lighted will cause heated gas to pass upward into chamber 3 around the peripheral edge thereby drying the garbage. When the garbage has become sufficiently dried the contents of compartment 100

3 can be dropped onto grates 24 and 25 by the rotation of shaft 10 by handle 21 which rotation carries plate 4 to the rear and by the cooperative scraping action of edge 7 of partition 5 and the plate 4 the garbage on the plate is scraped off and dropped on the grates. Scraper 19 also assists in this action by scraping the garbage from the partition member 5. Part of the garbage will fall on each grate and complete combustion can then be effected and the burning thereof may be utilized to dry additional garbage which is placed in the drying compartment. If there is an insufficient draft around plate 4, cover 38 can be removed from opening 37 and direct passage to the flue opening 12 is afforded.

While I have shown and described my invention in a preferred form, I am aware that various changes and modifications may be made without departing from the principles of my invention, the scope of which is to be determined by the appended claims.

I claim as my invention:

1. A device of the class described having an upper and a lower chamber, separating members therebetween comprising an upwardly extending partition at the back of the upper chamber and a plate at the lower edge of said partition, said plate being mounted to rotate on a vertical axis to drop material from the upper to the lower chamber.

2. A device of the class described having an upper and a lower chamber, separating members therebetween comprising an inclined partition at the back and a sector plate at the front, said plate being adapted to rotate under the lower edge of the partition and cooperable therewith to drop material from the upper to the lower chamber.

3. A device of the class described comprising a casing, having an inclined partition and a rotatable plate therein dividing the casing into upper and lower compartments, and a plurality of burners and grates in the lower compartment, said partition being secured at the top and sides to the interior of the casing and terminating at the bottom above the plate, said plate being rotatable about a vertical axis and cooperable with said partition to drop material from the upper to the lower compartment.

4. A device of the class described comprising a casing having an inclined partition and a rotatable plate therein dividing the casing into upper and lower compartments, and a plurality of burners and grates located in staggered relation in the lower compartment, partition being secured at the top and sides to the interior of the casing and terminating at the bottom above said plate, said plate having a peripheral drain groove and being cooperable with said partition to drop material from the upper to the lower compartment for combustion.

5. A device of the class described comprising a casing having an inclined partition and a rotatable plate therein dividing the casing into an upper drying compartment and a lower combustion compartment, said lower compartment having a plurality of offset grates, guide bars and burners, said partition having an aperture and a cover therefor in the upper portion thereof and having its lower portion terminating above said plate, said plate sloping downwardly from a central element thereof and having a peripheral drain groove therein.

6. A device of the class described comprising a casing having an inclined partition forming a hopper at the back therein and a rotatable plate at the front cooperable with said partition to form a drying compartment in the upper portion of said casing and to drop material from the said compartment to the space therebelow when said plate is rotated, a vertical shaft secured to said plate, a scraper for said hopper on said shaft, external operating means therefor, and a plurality of irregularly disposed burners, grates and guides in the lower portion of the casing.

7. A device of the class specified comprising a casing having a drying compartment at the top and a heating compartment therebelow separating elements comprising an inclined partition at the back forming a hopper and a rotatable plate at the front, a vertical shaft secured to said plate at the rear thereof, operating means therefor at the exterior of the casing, a supporting bearing for said plate and shaft, a scraper for the hopper secured to the shaft, said plate and scraper being cooperable with said partition to scrape material from the hopper and the plate when the shaft is rotated.

8. A device of the class specified comprising a casing having an inclined partition at the back and a rotatable plate at the front forming upper and lower compartments in the casing, said partition forming a hopper with the casing, said plate being adapted to close the lower outlet of the hopper having a peripheral drain groove and sloping upper surfaces, a vertical shaft secured to the plate, bearings and operating means therefor, a scraper for the hopper and cooperable therewith and with the plate to drop material from the upper into the lower compartment when the shaft, plate and scraper are turned.

EDWARD P. COLE.
